UNITED STATES PATENT OFFICE

2,607,978

MOLD FOR MAKING FIGURINES

Florence M. Ward, Pasadena, Calif.

Application March 5, 1949, Serial No. 79,881

1 Claim. (Cl. 25—129)

1

The present invention relates to an apparatus for making ceramic figurines.

In the manufacture of small decorative works of art of the type commonly known as figurines care and skill must be exercised to insure a product which is not only artistic but also free from flaws and defects. The making of such objects by hand eliminates many problems but results in high production cost. As there is a tremendous demand when reasonably priced they must be produced by mass production methods and the present invention relates to a method and to apparatus usable therein which enables the products to be so manufactured.

It is another object of the invention to provide an improved mold for making ceramic figurines commercially.

These and other more specific objects will appear upon reading the following specification and claim and upon considering in connection therewith the attached drawings to which they relate.

Referring now to the drawings:

Figure 1 is a view in perspective of the mold in which the figurine body is cast;

Figure 2 is a vertical section upon the line 2—2 of Figure 1;

Figure 3 shows the mold on its side with the upper section removed;

Figure 4 is an exploded view illustrating the figurine which has been made in the mold of Figures 1, 2 and 3 with the removable drain core separated therefrom;

Figure 5 is an exploded view illustrating the various additional elements which are attached to the main body portion;

Figure 6 shows the product in its completely assembled relationship with the various parts in place but prior to the step of applying the overglaze decorations; and

Figure 7 is a front view of the finished product.

In the drawings the mold used in practicing the invention is indicated generally by the reference character 10 and is seen to comprise half-sections 11 and 12 which are separable along abutting contoured central faces. The mold is made of water-absorbent material, plaster of Paris for example, which draws the moisture from the adjacent wet material being molded. This type of material is in common use in molding operations. The two half-sections 11 and 12 are hollowed out and cooperate to form a body cavity 13 and a connected skirt cavity 14. A removable drain core 16 is positioned within the latter and has a central inwardly extending

2

passage 17 through which clay in a fluid state can be poured. Near its outer enlarged end the core is formed with a flared portion 18 which fits within a mating surface 19 in the sections 11 and 12 to prevent the outward displacement of the mold. Relative shifting between the mold sections 11 and 12 is effectively prevented not only by the presence of the drain core 16, and by the irregularities of the contacting faces but also by the presence of recesses 21 on section 12 which interfit with raised portions 22 on section 11.

The object cast in mold 10 is removable, upon the separation of mold sections 11 and 12, with the drain core 16 which extends within its flaring skirt portion. The core is then displaced outwardly from the figure in the manner illustrated in Figure 4. In the performance of the molding operation providing the product thus far described is first assembled and positioned as illustrated in Figure 1 with the drain core 16 in place and sections 11 and 12 in contact. Fluid clay is then poured downwardly through opening 17 in the drain core to fill body cavity 13 and also the skirt cavity 14. The exact type of clay used is not important. It may be of an earthenware body or a china body, or any other suitable similar material.

After an initial drying period of about twelve minutes the mold is inverted end for end and all unsolidified material above the core 16 drains downwardly and outwardly through passage 17 leaving a wall conforming to the mold cavity the thickness of which is about equal to the thickness of the skirt cavity as illustrated in Figure 2. Moisture has been absorbed from that wall by the mold which has a moisture-absorbing characteristic as previously mentioned.

Following drainage the mold is permitted to stand in a dry atmosphere for about one hour during which time additional moisture is removed from the clay formed which then tends to shrink away from the mold cavity. At the end of the drying period the mold is placed upon its side and the upper section 12 is lifted off as illustrated in Figure 3. The lifting operation may be accomplished by inserting small rigid instruments between the abutting contacting faces but this is usually not necessary.

With the sections 11 and 12 separated, as illustrated in Figure 3, the molded form can be lifted from the supporting section by lifting the drain core 16. An easy method comprises inserting one or two fingers into the passage 17 and lifting gently upwardly. The figure comes from the

supporting cavity section, together with the drain core, and the two can then be separated as illustrated in Figure 4. The separation is aided by directing compressed air between the lower edge of the skirt and the flared core portion 18. The casting operation is then complete and the product is ready for subsequent steps in the process of making the complete figurine. First, however, the product is sponged and smoothed to eliminate irregularities.

Referring now to Figure 5, various so-called applied decorations to be attached are illustrated in their detached relationship and ready for attachment. The main portion formed as previously described is indicated generally by the reference character 26 and comprises the torso, arms, head, hat, and the voluminous flaring skirt. The various additional parts or applied decorations which must be attached include the legs or pantaloons section 27 which forms the pedestal of the unit and which extends upwardly under the flaring skirt as illustrated in Figures 6 and 7. The hands 28 are classified as applied decorations as is the ornamentation 29 which overlies a raised portion 31 upon the skirt and cooperates therewith to form a pocketbook or bag carried by the adjacent hand. A small neck piece 32 is positioned at the neck of the figurine and curls 33 are attached forwardly of the hat brim at the center of which is attached a feather-like ornamentation 34.

With the various applied decorations attached as described and as illustrated in Figure 6 the assembled figure is then fired in an oven in accordance with conventional practice following which it is dipped in a liquid glaze solution which deposits an even coat of glaze. The product is then again fired, baking the glaze into a hard glass-like surface.

Following the second firing, which is called the "gloss firing," the overglaze decorations are applied. Those decorations comprise the gold and china paint which are provided on the eyes, the mouth, the cheek, and also the precious metal decorations upon the body and skirt. The decorative fire which follows the last is of about five hours' duration. The various firings may vary in length but usually approximate seven or eight hours.

While the particular apparatus herein shown and described in detail is fully capable of attaining the objects and providing the advantages hereinbefore stated, it is to be understood that it is merely illustrative of the presently preferred

embodiments of the invention and that no limitations are intended to the details of construction or design herein shown other than as defined in the appended claim.

I claim:

A one-pour mold for figurines and the like comprising a pair of cooperative abutting sections formed in their opposed faces with recesses forming in their assembled relationship a central cavity closed at its inner end and enlarged at its top open end and defining from its inner end to its open end, in the order stated, the contours of the head, body, arms and voluminous skirt of a figurine, said sections being formed below said enlarged open end with core-supporting surfaces, and a drain core seated in said cavity, resting upon the core-supporting surfaces of said sections, and sealing the enlarged top open end of said cavity and spaced from the surrounding walls of said cavity below said end to define said skirt, said core being provided with a bore extending downwardly therethrough from its top to its bottom and opening into the portion of said cavity defining said body and at the junction of said body and said skirt, said bore serving as a filling and drainage port upon said mold being inverted and being sufficiently large to serve as a socket to receive a lifting force whereby a surrounding molded skirt and connected body can be lifted from a supporting mold section lying on its side and with the cooperating mold section first removed.

FLORENCE M. WARD.
